UNITED STATES PATENT OFFICE

MATTHIAS BROCK, OF BOSTON, MASSACHUSETTS, ASSIGNOR TO THE CONSOLIDATED & MCKAY LASTING MACHINE COMPANY, OF PORTLAND, MAINE.

HAND NAILING APPARATUS.

SPECIFICATION forming part of Letters Patent No. 601,942, dated April 5, 1898.

Application filed August 14, 1897. Serial No. 648,237. (No model.)

To all whom it may concern:

Be it known that I, MATTHIAS BROCK, of Boston, county of Suffolk, State of Massachusetts, have invented an Improvement in Hand 5 Nailing Apparatus, of which the following description, in connection with the accompanying drawings, is a specification, like letters and figures on the drawings representing like parts.

10 This invention relates to nailing apparatus of the type adapted to be held in or carried by one hand of the operator and operated by the other hand and commonly known as "hand-nailers" or "hand-tackers;" and the 15 object of the invention is to simplify and improve apparatus of this type, particularly with the end in view of rendering the action of the apparatus easier and less liable to be disarranged or broken under customary usage.

20 The several features of my invention will be hereinafter fully set forth in connection with the accompanying drawings and specification.

In the drawings, Figure 1 is a side elevation 25 of an apparatus containing one embodiment of my invention; Fig. 2, a left-hand edge view of Fig. 1; Fig. 3, a partial rear side view of Fig. 1; Fig. 4, a detail of the feed-actuating devices to be described.

30 Referring to the drawings in the embodiment of my invention there shown, A indicates a hand piece or case provided with a head A'; d, a driver arranged within the case and indicated only by dotted lines, Fig. 3; d², 35 a driver actuator or carrier having a suitable striking-cap d⁶; A⁶, the nose through which the tacks or fastenings are driven into the work, and A² the raceway, all of which may be of any suitable or desired construction—

40 such, for instance, as shown in Letters Patent of the United States, No. 537,269, issued to me April 9, 1895, to which reference may be had for a description of the operation of such parts, although it is to be understood my invention, to be hereinafter described, is not 45 restricted to its use in connection with this particular mechanism, the latter being shown merely as an example of any mechanism of this type to enable my invention to be understood.

M indicates a suitable hopper or receptacle for the tacks or other fastenings to be used with the nailing apparatus to be described. This hopper or receptacle may be of any suitable or desired construction, it being herein 55 shown as mounted to rotate upon a pivot m, extended from the raceway A², rotation of the hopper acting in any suitable manner, as will be understood by those skilled in the art, to deliver the fastenings contained therein to 60 said raceway, through or along which they are delivered to the driving mechanism.

I have herein shown a rotary hopper; yet it will be understood that some parts of my invention may be equally well applied to other 65 forms of hopper or receptacle wherein a rotary movement of some part is employed directly or indirectly to govern or control the delivery of the fastenings on the raceway leading to the driving mechanism.

The hopper or receptacle M is shown as provided with a sprocket-wheel 10, which is embraced by a flexible connection, shown as a sprocket-chain 11, surrounding a sprocket-wheel 12, loose on the outer end of a short 75 shaft or arbor 13, upon which said wheel 12 is retained by a suitable nut 14. Fast on this shaft 13, immediately behind the wheel 12, is a pawl-carrier 15, to which is pivoted the pawl 16, maintained by a spring 17 in 80 normal engagement with a series of ratchet-teeth 18, upon or secured to the rear side of the sprocket-wheel 12, oscillation of the shaft 13 and its pawl-carrier 15 causing the pawl 16 to impart a step-by-step rotation to the 85 ratchet-wheel 18, its sprocket-wheel 12, and through the chain 11 a corresponding step-by-step rotation to the sprocket-wheel 10 and delivery-controlling means M.

The shaft 13 referred to is provided at its 90 end opposite the pawl-carrier 15 (see Fig. 3) with a laterally-extended arm 19, acted upon by a spring 20, which maintains the said arm normally pressed against the depending free end of the feed-lever 21, pivoted at 22 within 95 the inclosing case A.

When the actuator or carrier d² is depressed in the act of driving a fastening, the lower end thereof (see dotted lines, Fig. 3) acts upon the inwardly-inclined feed-lever 21 and 100

forces the latter gradually back or to the right, Fig. 3, it in turn acting upon the arm 19 on the shaft 13 to rotate said shaft and actuate the ratchet-wheel 18 and parts controlled thereby, as described. A suitable detent 30 acts to prevent retrograde movement of the ratchet-wheel 18.

It will readily be seen that however sharp or violent the downward or driving movement of the driver actuator or carrier ^{d2} the movement of the feed-lever 21 as it is forced to one side is always gradual, and said lever is consequently relieved of most if not all of any shock or impact received by the actuator, and therefore the feeding movement of the parts described is also relieved of any impact or blow. In this way the feeding devices actuate more easily and with less violence than heretofore. Further than this the feeding movement by the parts described is so gradual, however sharp be the movement of the actuator, that the parts are set in motion and perform their work with no perceptible jar or effect upon the actuator. In other words, the operator in delivering the blow upon the actuator feels no jar of the feeding devices as the latter operate in feeding the fastenings. To make this clearer, it may be further stated that in devices of this class as heretofore constructed the feeding devices have been actuated at or about the time of the greatest resistance to the movement of the actuator by the driving of the tack, and to such resistance there is added the further resistance of the feeding devices performing their work, which always gives to the actuator an uneven movement distinctly and injuriously felt by the hand of the operator. In my improved device, however, it will be noticed that the feeding movement commences immediately on the descent of the actuator, and the movement of such feeding devices from that time until completed is so gradual that their action is not perceptibly felt by the operator.

Heretofore in devices of this character it has been common to transform the reciprocating movement of the actuator into rotary movement of the feeding devices through the intervention of levers, usually of considerable length, and by reason of their length having considerable movement at their free ends, thus necessitating more or less lost motion between the ends of the levers and the parts actuated thereby to insure certainty of operation without too nice adjustment. This lost motion or looseness causes impacts which are distinctly felt by the operator. In this invention, however, it will be noticed that the reciprocating movement of the actuator is transformed into rotary movement at a point close to the said actuator on the casing A, and a slight reciprocatory movement—as, for instance, that of the feed-lever 21—is therefore sufficient to provide the necessary rotary movement—as, for example, of the sprocket-wheel 12—thereby reducing the amount of

lost motion and correspondingly eliminating the contacts or shocks which would result from the use of parts of greater length and having greater movements with more lost motion. All these features combined give to the device herein described as embodying my invention a smoothness and an ease of operation heretofore quite unknown in apparatus of this character.

By the use of a flexible connection, as the sprocket-chain 11, for transmitting the motion from the feed-actuating device to the actual feed-controlling part, as the part M, a certain flexibility is had which prevents injury should the apparatus meet with accident, as by dropping upon the floor or otherwise, whereas connecting-levers as heretofore used would very generally be bent, broken, or thrown out of adjustment by a blow that would in no wise injure my present device. The use of the flexible connection also of course renders the device somewhat lighter and greatly simplifies the mechanism, making it cheaper and easier to clean.

In order to maintain the flexible connection under proper tension at all times, I have herein provided a wheel 25, mounted upon the free end of an arm 26, fulcrumed at 27 on the head of the machine and held in adjusted position by a set-screw 28, passed through a slot 29 in the arm referred to and screwed into the said head.

My invention of course is not restricted to the embodiment herein shown, for the same may be varied without departing from the spirit and scope of the invention.

Having described my invention, what I claim as new, and desire to secure by Letters Patent, is—

1. In a hand nailing apparatus, the combination with a driver and a driver-actuator, of means for controlling the supply of nails to said driver, and an endless flexible connection traveling always in one direction interposed between the said driver-actuator and nail-controlling means, and through which the latter is actuated by the former.

2. In a hand nailing apparatus, the combination with a driver and a reciprocating actuator therefor, of a loose nail-holding receptacle, means controlling the supply of nails therefrom to said driver, and a flexible connection traveling always in one direction interposed between the said driver-actuator and nail-controlling means, and through which the latter is actuated by the former.

3. In a hand nailing apparatus, a reciprocating driver and its actuator, rotary means located at one side of said driver and more or less removed therefrom, to control the supply of nails to said driver, and means to conduct the nails from said rotary nail-controlling means to said driver, combined with means closely adjacent the said driver and its actuator for transforming the reciprocating movement of the latter into a rotary motion, and connections between such means and said

nail-controlling means for operating the latter by or from the former, said connections being independent of said controlling means, substantially as described.

5. 4. In a hand nailing apparatus, a case containing a reciprocating driver, a driver-actuator, a rotary nail-controlling part carried by said case, and means to conduct the nails from said nail-controlling part to said driver, combined with means for obtaining a rotary movement by and from the reciprocating movement of said driver or its actuator, and a flexible connection joining such means with and to rotate said nail-controlling part, said flexible connection being independent of said nail-conducting means, substantially as described.

5. In a hand nailing apparatus, a case, a reciprocating driver, its actuator, a rotary feed-controlling part, means to conduct nails therefrom to said driver, and means independent of said nail-conducting means and actuated by said driver and including a flexible connection, for transforming a step-by-step rotary movement always in one direction to said feed-controlling part from said driver or its actuator, substantially as described.

6. In a hand nailing apparatus, a case, a reciprocating driver, and its actuator, a wheel journaled on said case, and devices moved by said actuator to impart a step-by-step rotation to said wheel, a rotary nail-receiving hopper also mounted on said case, and an endless connection joining the same with and to be rotated by said wheel, substantially as described.

7. In a hand nailing apparatus, a case, a reciprocating driver, and its actuator, a wheel, and devices to impart a step-by-step movement thereto from said actuator, a rotary feed-

controlling hopper, and a flexible connection positively rotating the same from the said wheel, substantially as described.

8. In a hand nailing apparatus, a case, a reciprocating driver and its actuator, a swinging lever arranged to be moved by said actuator, a wheel and a pawl-and-ratchet mechanism interposed between the same and the said lever, a rotary feed-controlling hopper, and a sprocket-chain connecting the same with and to be driven by said wheel, substantially as described.

9. In a hand nailing apparatus, a hand-operated reciprocating driver, and a suitable case, of a rotary nail-controlling part carried by said case, and connections interposed between the said nail-controlling part and said driver and including an endless flexible connection, whereby hand-operated reciprocation of the said driver transmits therefrom through the said flexible connection a rotary movement to the said nail-controlling part.

10. In a hand nailing apparatus, the combination with a suitable case, and a hand-operated driver arranged therein, of a loose nail-holding receptacle, a raceway to conduct the loose nails therefrom to driving position adjacent the said driver, a rotary feed-controlling part governing the flow of the loose nails to said raceway, and an endless flexible connection interposed between said driver and said rotary nail-controlling part for operating the latter by hand-operated movement of the former.

In testimony whereof I have signed my name to this specification in the presence of two subscribing witnesses.

MATTHIAS BROCK.
